UNITED STATES PATENT OFFICE.

TIMOTHY ROSE, OF CORTLANDVILLE, NEW YORK.

CANAL-BOAT PROPELLER.

SPECIFICATION forming part of Letters Patent No. 226,931, dated April 27, 1880.

Application filed March 4, 1880. (No model.)

To all whom it may concern:

Be it known that I, TIMOTHY ROSE, of the town of Cortlandville, in the county of Cortland and State of New York, have invented 5 certain new and useful Improvements in Canal-Boat Propellers; and I do hereby declare that the following is a full, clear, and exact description of the invention, which will enable others skilled in the art to which it appertains to 10 make and use the same, reference being had to the accompanying drawings, and to the letters of reference marked thereon, which form a part of this specification.

My invention relates to an improvement to 15 be used in the propulsion of canal-boats by steam-power.

In the drawings, Figure 1 represents a perspective view of the tube and water-chamber, and Fig. 2, perspective and cross-section views 20 of the machinery inside of the tube.

The letter A indicates the tube, which extends lengthwise through the body of the boat, and open at each end, and B the water-chamber, which rises above the surface of the water.

25 The tube A being open at both ends, the water flows freely through, and thus permits the boat to be propelled by suitable machinery inside of the tube A. The letter C indicates the piston-rod, which plays horizontally, carrying the perpendicular shaft S back and forth 30 in the tube A. Connected to the shaft S are wings F F, so hung upon the shaft as to easily open and shut.

The piston-arms e e are secured to the shaft 35 S both above and below the wings F F. These wings are so arranged and connected to the shaft that when forced forward the resistance of the water opens them and, nearly filling the tube, they gather the water and 40 force it out of the tube, thus furnishing a resistance and power which propel the boat. When the piston-rod returns the force and resistance of the water shut the wings, so as to

permit them to pass through the water in the tube without producing a counter action. 45

A hood, H, secured to the shaft S, guards the rear of the wings, and by means of lateral extensions or braces a a, forming a part thereof, coming in contact with flanges b b upon the sides of the wings F F, the wings are prevented from opening beyond the desired angle or position. Between the wings is a stop, D, to prevent them closing completely together when withdrawn by the return stroke of the piston. 50

By turning the shaft S one-half around, which may be done by any suitable machinery, the action of the water-wings is reversed and the boat propelled in an opposite direction. 55

In the bottom of the tube A is a groove or 60 channel, e, through which the base of the shaft S is carried. In place of the groove e, a single rail may be used, fitting into a slot in the base of the shaft S, to direct its course.

Having thus described my invention, what 65 I claim, and desire to secure by Letters Patent, is—

The combination, with the tube and water-chamber, of the vertical shaft working in ways or guides and carrying the vibrating wings 70 provided with flanges b b, the hood H, formed with lateral extensions or braces a a, for the purpose, in connection with flanges b b, of preventing the said wings from opening beyond the desired angle, and the stop D, for preventing the wings from closing entirely when withdrawn by the return stroke of the piston-rod, all arranged and combined to operate substantially as and for the purposes set forth. 75

In testimony that I claim the foregoing as 80 my own I affix my signature in presence of two witnesses.

TIMOTHY ROSE.

Witnesses:

R. H. DUELL,
CLARA OWEN.
